Stockton LLP

(57) **CLAIM**

The ornamental design for a coffee beverage cap as shown
and described.

DESCRIPTION

FIG. 1 is a top perspective view of a coffee beverage cap
showing our new design;

FIG. 2 is a bottom perspective view of the coffee beverage
cap of FIG. 1;

FIG. 3 is a front side elevational view of the coffee beverage
cap of FIG. 1;

FIG. 4 is a rear side elevational view of the coffee beverage
cap of FIG. 1;

FIG. 5 is a left side elevational view of the coffee beverage
cap of FIG. 1;

FIG. 6 is a right side elevational view of the coffee beverage
cap of FIG. 1;

FIG. 7 is a top side view of the coffee beverage cap of FIG.
1;

FIG. 8 is a top side view of the coffee beverage cap of FIG.
1; and,

FIG. 9 is a cross-sectional side view taken along cut line 9-9
in FIG. 3.

The broken lines in the drawings depict portions of the
coffee beverage cap that form no part of the claimed design.

1 Claim, 9 Drawing Sheets
